BOARD GAME

Theodore H. Rapoport, Summit, Ill.

Application June 19, 1950, Serial No. 10,628

Term of patent 14 years

(Cl. D34—5)

To all whom it may concern:

Be it known that I, Theodore H. Rapoport, a citizen of the United States, residing at Summit, in the county of Cook and State of Illinois, have invented a new, original, and ornamental Design for Board Game, of which the following is a specification, reference being had to the accompanying drawing, forming part thereof.

The figure is a plan view of a board game, showing my new design.

The board is of conventional thickness.

I claim:

The ornamental design for a board game, as shown and described.

THEODORE H. RAPOPORT.
